United States Patent Office

Des. 225,670
Patented Dec. 26, 1972

225,670

PLATE OR THE LIKE

Ottorino N. Mercadante, Corning, N.Y., assignor to Corning Glass Works, Corning, N.Y.

Continuation of design applications Ser. No. 22,757 and
Ser. No. 22,760, both May 1, 1970. This application
Jan. 25, 1971, Ser. No. 109,728

Term of patent 14 years

Int. Cl. D7—01

U.S. Cl. D44—15

Fig. 1

Fig. 2

FIG. 1 is a top plan view of a plate of conventional configuration showing my new design.

FIG. 2 is a top plan view of a plate of conventional configuration showing a further embodiment of my new design.

This is a continuation of design applications Ser. Nos. 22,757 and 22,760, both filed May 1, 1970, and both now abandoned.

I claim:

The ornamental design for a plate or the like, as shown and described.
